UNITED STATES PATENT OFFICE

163,304

CHILD'S APRON

Charlotte McEwen, Ottawa, Ontario, Canada

Application December 13, 1950, Serial No. 13,421
In Canada August 4, 1950

Term of patent 14 years

(Cl. D3—26)

To all whom it may concern:

Be it known that I, Charlotte McEwen, a citizen of the Dominion of Canada, residing at Ottawa, Province of Ontario, Dominion of Canada, have invented a new, original, and ornamental Design for a Child's Apron, of which the following is a specification, reference being had to the accompanying drawing, forming part thereof.

In the drawing:

I claim:

The ornamental design for a child's apron, as shown.

CHARLOTTE McEWEN.
